WORK GLOVE FORM

Robert C. Palicki, Toledo, Ohio

Application July 10, 1935, Serial No. 30,747

4 Claims. (Cl. 18—41)

This invention relates to forms used in the manufacture of coated gloves, and especially to a form adapted to support a fabric glove, which is dipped or otherwise coated with rubber.

5 An object is to produce a simple and inexpensive glove form for use in the manufacture of coated gloves, which enables the gloves to be readily and conveniently slipped or removed from the form after the coating operations have been completed.

10 Another object is to produce a glove form having the new and improved features of construction and arrangement hereinafter described, and, for purposes of illustration, an embodiment 15 of the invention is shown on the accompanying drawing, in which:

Figure 1 is a top plan view of a glove form showing the thumb piece dotted in;

20 Figure 2 is a vertical sectional elevation on the line 2—2 of Figure 1;

Figure 3 is a perspective view of the thumb viewed from the underside; and

25 Figure 4 is a side elevation showing the form mounted in position to remove the coated glove therefrom.

Referring to the drawing, the reference numeral 10 designates a substantially rigid form, which is preferably of metal, such as aluminum, and having the general shape of a glove. The 30 form is hollow and is provided with a plurality of perforations 11, an opening 12 being provided in the lower portion to permit evaporation of the liquids used in coating the glove. An opening 13 is also provided in one side of the glove form for this purpose.

35 Connected to the wrist portion of the glove form is a U-shaped handle or mounting 14, which, as shown in Figure 4, may be placed over a hook 15 to permit a coated glove to be slipped 40 from the form. The handle or mounting portion 14 is also used in supporting the form during the coating operations.

Provided on opposite sides of the glove form in the region of the thumb, are longitudinally 45 elongate slots 16, into which spaced lugs 17 on a thumb piece 18 are adapted to extend. It will be understood that the thumb piece is disposed at one side or the other of the glove form, depending upon whether the glove is right or left hand. The thumb piece 18 is also of cast metal, such as aluminum, and is open at its under side, as indicated at 19, as well as between the lug portions 17, as indicated at 20. It should be noted that the lug portions project outwardly 50 from a substantially rectangular surface 21, which

is adapted to abut against the form 10. In this position the outer end of the thumb portion inclines upwardly and outwardly from the form 10, as indicated in Figure 2, adequate space being afforded between the underside of the thumb piece and the form to leave these portions exposed for coating.

The above described form is particularly useful in the coating of fabric work gloves with latex solutions, and in practice the thumb piece 10 18 is first inserted in the thumb of the glove and thereupon the glove is slipped over the form 10, the spaced lugs 17 engaging in one or the other of the slots 16, which serve to position the thumb piece properly. After the coating has been accomplished the glove tends to adhere to the form, but to enable the same to be slipped therefrom a slight tilting and lifting movement to the thumb 15 disengages the thumb piece 18 from the form, enabling the coated glove to be pulled off with 20 the thumb piece 18 still within the glove. Thereafter the thumb piece can readily be removed or will drop out of the glove. Figure 4 shows a work glove W on the form in position to be pulled off.

It is to be understood that numerous changes 25 in details of construction, arrangement and operation may be effected without departing from the spirit of the invention, especially as defined in the appended claims.

What I claim as new and desire to secure by 30 Letters Patent is:

1. A glove form of the character described comprising a hollow body having the general shape of a glove and provided with a longitudinal slot in the region of the thumb, and a separate thumb 35 piece having a part extending into said slot, tiltable about an axis transverse to the slot, and removable with the glove when the latter is slipped from the form.

2. A glove form of the character described comprising a perforated hollow body having the general shape of a glove, and a separate thumb piece having spaced elements in sliding engagement with said body and mounting the thumb piece 45 upon the body tiltably about an axis transverse to the longitudinal axis of said thumb piece.

3. A glove form of the character described comprising a hollow body having the general shape of a glove and provided with a longitudinal slot 50 on opposite sides in the region of the thumb, and a separate thumb piece having a part engageable in one slot or the other and mounting the thumb piece upon the body tiltably about an axis transverse to the longitudinal axis of said thumb 55

piece, said thumb piece being removable with the glove when the latter is slipped from the form.

4. A glove form of the character described comprising a hollow body having the general shape of a glove and provided with a longitudinal slot on opposite sides in the region of the thumb, and a separate thumb piece having spaced lugs adapted to enter either of the slots and a flat

base adapted to contact the form on the sides of the slot into which the lugs project, said abutting area being arranged to normally support the thumb piece with its free end projecting at an angle to the form, whereby said thumb piece may be removed from the rest of the form by tilting it about an axis transverse to the longitudinal axis of the thumb piece. 5
